United States Patent Office.

WILLIAM GORMAN, OF NEW BRITAIN, CONNECTICUT, ASSIGNOR TO RUSSELL & ERWIN MANUFACTURING COMPANY, OF SAME PLACE.

Design No. 4,034, dated May 17, 1870.

DESIGN FOR A FACE-PLATE FOR LOCKS FOR SLIDING DOORS.

The Schedule referred to in these Letters Patent and making part of the same.

To all whom it may concern:

Be it known that I, WILLIAM GORMAN, of New Britain, in the county of Hartford and State of Connecticut, have invented and designed a new Design for Face-Plate for Locks for Sliding Doors; and I do hereby declare that the following is a full, clear, and exact description thereof, reference being had to the drawings making a part of this specification.

In the accompanying drawings—

Figures 1 and 2 represent respectively the face-plates used with locks for sliding doors.

A A are the mortises for the insertion of the spring pulls for working the doors.

B B the mortises for the spring buttons, which, when pressed, allow the pulls, which are held back by a catch, to be projected beyond the face-plate, and

C C are the mortises for the accommodation of the curved lock-bolt.

The characteristics of the design for the two face-plates are the same.

The edges of the lips A A are surrounded by a raised band, a, and the interior space is filled with leaf-work b, in relief, on a matted ground.

The several mortise openings are also surrounded by a plain band, c, and the intermediate spaces are filled with scroll and leaf-work in relief, as shown.

What I claim as my invention, and desire to secure by Letters Patent, is—

The design for the face-plate for locks for sliding doors, herein described and shown in the drawings.

WILLIAM GORMAN.
